(57) **CLAIM**

The ornamental design for an electrical power inlet connection device, as shown and described.

DESCRIPTION

FIG. 1 is a top perspective view of an electrical power inlet connection device;

FIG. 2 is a bottom perspective view thereof;

FIG. 3 is a front elevational view thereof;

FIG. 4 is a right elevational view thereof;

FIG. 5 is a top plan view thereof; and,

FIG. 6 is a bottom plan view thereof.

A left side elevational view is not shown because it is a mirror image view of the right side elevational view shown in FIG. 4.

The ornamental design which is claimed is shown in solid lines in the drawings. The broken lines shown in the drawings are for the purpose of illustrating environment and form no part of the claimed design.
